(57) **CLAIM**

The ornamental design for a vehicle headlight, as shown and described.

DESCRIPTION

FIG. 1 is a perspective view of a vehicle headlight;

FIG. 2 is a left side view thereof;

FIG. 3 is a front view thereof;

FIG. 4 is a right side view thereof;

FIG. 5 is another perspective view thereof; and,

FIG. 6 is a top view thereof.

The broken lines shown in the drawings represent portions of the vehicle headlight that form no part of the claimed design.

The claim is also for a mirror image of the vehicle headlight that is not shown.
